UNITED STATES PATENT OFFICE

CELESTINO ROSATELLI, OF TURIN, ITALY, ASSIGNOR TO FIAT SOCIETÀ ANONIMA, OF TURIN, ITALY

TRIANGULAR PLANE GIRDER FOR AEROPLANES

Application filed December 11, 1930, Serial No. 501,711, and in Italy September 23, 1930.

This invention relates to a triangularly braced girder having the characteristic feature that fully free pentagonal apertures are provided therein which exceed the normally admissible size and substantially reach the height of the girder itself, without imposing excessive stresses on the girder members.

According to this invention this is obtained by a special arrangement of the members of the braced girder which is in accordance with the known statical graphical law expressed by the formula

$$X=2Y-3$$

15 wherein X is the number of members and Y the number of knots of the girder.

As it is well known the above mentioned formula expresses the necessary and sufficient condition enabling a braced girder to be statically determined and undeformable.

20 The accompanying drawing shows diagrammatically by way of example a girder construction for an aeroplane fuselage, in which the apertures for the entrance doors are formed without the necessity of employing special means for reinforcing the girder and without effecting the stability of said girder.

Figure 1 shows diagrammatically a part 30 of the girder forming the side wall of the fuselage.

Figure 2 is a general view of an aeroplane, of which the fuselage is constructed with the girder shown in Fig. 1.

35 Referring to the drawing: A_1 and A_2 denote the two fully free large pentagonal apertures in correspondence with which the doors s and s , (Fig. 2) shall be fitted. The apertures A_1 and A_2 divide the girder into 40 three sections; considering in such section the parts B C F E D, E G H I L M and M N O P Q and referring to the members as a and to the connections as n it will be found that $a=33$ and $n=18$

45 The said values fulfill the necessary and sufficient condition for obtaining a statically determined and undeformable girder. In fact $33=2 \times 18 - 3$

Of course the above described system may 50 be applied in cases other than that mentioned

above without departing from the spirit of this invention.

What I claim is:

In an aircraft body having lateral openings for the doors extending a substantial portion of the height of the body, a longitudinal truss at a side of the body and having openings corresponding with the body openings, said truss comprising upper and lower beams extending continuously throughout the portion of the body in which said door openings are located, uprights connecting said beams between said openings, a horizontal member for connecting intermediate points of said uprights, diagonal struts between said uprights converging towards the connecting point of this horizontal member with one of said uprights, and struts between the connecting points of said horizontal member and the lower beam.

In testimony that I claim the foregoing as my invention, I have signed my name.

CELESTINO ROSATELLI.
